UNITED STATES PATENT OFFICE

121,151

DESIGN FOR A PAIR OF PARTIALLY RIMLESS SPECTACLES

Arthur F. Williams, St. Paul, Minn., assignor to
Wils-edge Corporation, St. Paul, Minn., a cor-
poration of Minnesota

Application March 4, 1939, Serial No. 83,341

Term of patent 14 years

To all whom it may concern:

Be it known that I, Arthur F. Williams, a citizen of the United States, residing at St. Paul, county of Ramsey and State of Minnesota, have invented a new, original, and ornamental Design for a Pair of Partially Rimless Spectacles, of which the following is a specification, reference being had to the accompanying drawing, forming part thereof.

Figure 1 is a front view of a pair of partially rimless spectacles showing my new design.

Figure 2 is a top view; and

Figure 3 is an edge view at the nasal side of the spectacles.

The temples are broken away in Figures 2 and 3 for convenience of illustration.

The essential features of my design reside in partially rimless spectacles in which the free arm is attached to the upper portion of the panel member, and the bridge and nose rest are attached to the lower portion of said panel member, all as shown.

I claim:

The ornamental design for a pair of partially rimless spectacles, as shown and described.

ARTHUR F. WILLIAMS.
